BOOKSHELF UNIT

Orestes M. Davey, Hartford, Conn., assignor to The Stanley Works, New Britain, Conn.

Filed Sept. 9, 1969, Ser. No. 19,073

Term of patent 14 years

Int. Cl. D6—01

U.S. Cl. D33—3

FIG. 1

FIG. 2

FIG. 3

FIG. 4

FIG. 1 is a perspective view of a bookshelf unit showing my new design;

FIG. 2 is a side elevational view thereof;

FIG. 3 is a sectional view of one of the vertical post members looking in the direction of the arrows 3—3 of FIG. 1; and

FIG. 4 is a sectional view of the horizontal member taken along the line 4—4 of FIG. 1.

The shelf tops not shown in FIG. 1 are plain and unornamented.

I claim:

The ornamental design for a bookshelf unit, as shown and described.
